PUMP ANCHOR STRUCTURE

Ernest W. Ostrom, Pasadena, and Glynn H. Williams, Huntington Park, Calif., assignors to Axelson Manufacturing Co., Los Angeles, Calif., a corporation of California

Application March 16, 1936, Serial No. 69,086

5 Claims. (Cl. 103—181)

This invention relates to well equipment, and particularly to the construction of anchors for supporting pumps in wells.

A broad object of the invention is to simplify the construction of pump anchors and increase their efficiency.

Other more specific objects, together with various features of the invention, will be disclosed in the detailed description of the invention which follows.

Pump anchoring structures of the general types to which this invention relate have two general functions to perform:

(1) to detachably retain the pump in the desired position in the tube; and

(2) to effect a seal between the pump and tubing so that pumped fluid will not return past the pump.

Heretofore it has been the common practice to provide a seat in the tubing and a cooperating seat on the pump which rests on the tubing seat thereby preventing downward movement of the pump and at the same time sealing about the pump. To prevent upward movement of the pump away from the seat, it was customary to provide a separate spring latch for releasably locking the pump down against its seat.

In accordance with the present invention, we provide an anchor construction in which the tubing-seat and locking member are formed in one piece, which is clamped in the tubing, thereby producing a structure which is simple, inexpensive, easy to install and remove, and at the same time is very effective in use.

35 In the drawing:

Figure 1 is an elevational view, partly in section, showing a pump and tubing incorporating an anchoring structure in accordance with the invention;

40 Fig. 2 is an enlarged detail sectional view of the anchoring structure disclosed in Fig. 1;

Fig. 3 is a cross section taken in the plane III—III of Fig. 1;

45 Fig. 4 is a partial view similar to Fig. 1, showing certain modifications of the structure depicted in Fig. 1; and

Fig. 5 is a cross section taken in the plane V—V of Fig. 4.

50 Referring to Fig. 1, there is shown a pump comprising a barrel 1 positioned within a section of tubing 2, the upper portion of which is perforated to permit entry of oil from the surrounding sands.

The tubing 2 is closed at the lower end by a cap 55 6 and constitutes a sand trap, the functions of

which are well known to those skilled in the art.

The upper end of the tubing 2 is screwed into the lower end of an anchor-supporting coupling member 7 and a second anchor-supporting coupling member 8 is screwed into the upper end of the member 7. The member 8 is internally threaded at the upper end to receive the lower end of a string of tubing which is adapted to extend upwardly through the well to the surface.

A rod guide 9 is secured to the upper end of the pump barrel 1 and serves to guide a pump rod 10, which is to be connected by an adapter 10a to the lower end of a string of sucker rods extending through the tubing to the surface. The rod 10 is connected to a plunger within the barrel. However, the internal construction of the pump constitutes no part of the present invention and is therefore not disclosed.

Referring now to Fig. 2, it will be observed that the upper end of the pump barrel is screwed onto a collar 11 which in turn is secured at its upper end by screw threads to the lower end of a tubular supporting member 12. The rod guide 9 in turn is secured by screw threads to the upper end of the member 12.

The member 12 functions not only as a connecting member between the collar 11 and the rod guide 9 but also as a support for the entire pump barrel. To this end the member 12 is enlarged adjacent its upper end, to define an annular tapered shoulder 13 which rests against and seals with an anchor ring 14 which in turn is secured in the tubing by being clamped between the coupling members 7 and 8, respectively. The ring 14 is provided with a beveled edge 13a which seals with the shoulder 13 on the tubular member 12. The ring 14 is provided with a narrow (in a radial direction) outwardly extending flange 15 which fits snugly within the upper end of the coupling member 7 but rests against and is supported vertically by a shoulder 16 in the coupling member 7. Thus the latter is of smaller internal diameter below the shoulder 15 than at the threaded upper end. As clearly shown in Fig. 2, the lower end of the upper coupling member 8, when the latter is screwed into the lower coupling member 7, bears against the top of the ring 14 and locks it tightly against the shoulder 16 on the member 7. The upper end of the ring 14 and the under edge of the flange 15 thereon are ground smooth to form fluid-tight seals with the coupling members 8 and 7, respectively, so that there can be no leakage of fluid around the ring 14. It is understood of course that the seat-

30

35

40

45

50

55

ing surfaces 13 and 13^a are likewise ground smooth to effect a fluid-tight seal.

To normally secure the pump against its seat, there are provided hold-down fingers 17 on the ring 14, these fingers being formed integrally with the ring and extending downwardly and inwardly therefrom. The lower ends of these fingers 17 are beveled as shown at 18 and, when the pump is installed, bear against an annular shoulder 19 thereon, which shoulder may be constituted by the lower wall of an annular recess 20 cut in the tubular member 12. By virtue of the bevel ends 18 the fingers 17 may be urged outwardly by placing sufficient lifting strain on the tubular member 12, thereby permitting removal of the pump from the tubing without pulling the tubing. However, the tension of the fingers 17 is sufficient to hold the pump in place during all ordinary pumping operations.

20 As shown in Fig. 1, the annular shoulder 13 of the pump is positioned closely adjacent the upper end thereof. Likewise the fingers 17, being formed integrally with the ring 14, are closely adjacent to the seat 15 so that the pump is supported at two closely spaced points positioned adjacent the upper end of the pump. For all practical purposes, the pump may therefore be considered to be suspended from its upper end. This permits the pump to readily align itself with the pump rod 10 and also prevents sand from packing about the pump barrel, which would interfere with removal of the pump.

30 A particular advantage of the invention results from the fact that the ring 14, bearing the seat 15 and the hold-down fingers 17, are constituted by a single element which is anchored to the tubing by being clamped between the coupling members 7 and 8.

Another advantage of the structure described 40 is that the ring member 14 has no threads thereon. This is advantageous by virtue of the fact that it is desirable to harden the seat 15, and difficulty is often encountered in hardening an element having screw threads thereon because 45 the hardening treatment often distorts the threads.

The structure disclosed in Figs. 4 and 5 is similar in all respects to that already described with reference to Figs. 1 to 3 except for the construction 50 of the tubing 2 and the mode of attaching it to the coupling member 8'.

Thus in Figs. 4 and 5 the tubing 2' is internally threaded at the upper end, as shown at 30, and screws directly onto the lower end of coupling member 8', thereby eliminating the coupling member 7 of Figs. 1 and 2. This construction permits the tubing 2' of Fig. 4 to have a larger diameter than the tubing 2 of Fig. 1, thereby providing more space for fluid between the tubing 60 and the pump barrel. However, this increased spacing between the pump barrel and tubing might permit rocking or swinging movement of the barrel on its seat in excess of that necessary for proper alignment, and it is therefore desirable 65 to provide guides in the tubing 2' adjacent to but above the lower end of the pump barrel. As shown in Figs. 4 and 5, these guides 31 are four in number and consist of lugs which may either be formed integrally with, or welded to, the tubing 2. The radial dimensions of the lugs are such as to permit a limited lateral movement of the pump barrel 1', therebetween.

The invention has been described with reference to particular embodiments, which have been 75 found satisfactory in service. It is obvious, how-

ever, that various changes can be made from the particular structures shown in the drawing without departing from the invention, and the latter is therefore to be limited only as set forth in the appended claims.

5

We claim:

1. In a pump structure adapted to be inserted in tubing in a well, an annular ring member adapted to be mounted in the tubing, said member projecting inwardly beyond the inner circumference of 10 the tubing and having a seating surface at its inner upper edge and having a plurality of resilient fingers formed integrally therewith and extending downwardly and inwardly therefrom, a tubular pump barrel having a lower portion dimensioned to pass through said ring member and having a beveled outwardly extending annular shoulder above said lower portion adapted to engage and rest upon the seating surface of said ring member and said barrel member also having 20 a second beveled shoulder thereon so positioned below said first mentioned shoulder as to be engaged by the ends of said fingers when said first shoulder is seated against said annular ring.

2. A pump constructed as described in claim 1, 25 in which said shoulders on said pump barrel are positioned closely adjacent the upper ends thereof whereby said barrel member is substantially freely suspended in the tubing from its upper end and is thereby relieved of compressive and bending 30 strains.

3. An anchor structure for insertion in well tubing to support a pump provided with a seating shoulder and an annular shoulder therebelow for receiving resilient hold-down fingers, said anchor 35 structure comprising a pair of coupling members adapted to be joined together and inserted in a tubing string, one of said members being threaded internally at one end and having an inwardly extending annular shoulder below said internally 40 threaded portion and the other member having an externally threaded end portion of reduced diameter adapted to screw into the internally threaded end portion of the first member, and a pump-engaging member comprising a ring adapted to fit within the said first coupling member and having an external flange thereon adapted to be clamped between said shoulder on said one coupling member and the end of the other coupling member when the coupling members are 45 screwed together, said ring defining at its upper inner edge a pump-engaging seat and having formed integrally therewith, downwardly and inwardly extending hold-down fingers for engaging a pump below but closely adjacent the seat there- 55 on.

4. An anchor structure for insertion in well tubing to support and enclose a pump provided with a seating shoulder and an annular groove therebelow for receiving resilient hold-down fingers, said anchor structure comprising a coupling member adapted to be attached to the lower end of a tubing string, said member being externally threaded at the lower end and the lower end defining a shoulder, a tubing section adapted to 60 enclose a pump, the upper end of said section being internally threaded and having an inwardly extending annular shoulder at the base of the threaded portion, a pump engaging member comprising a ring adapted to fit within the upper end 65 of said tubing section and having an external flange thereon adapted to be clamped between said annular shoulder on said tubing section and the lower end of said coupling member when the tubing section and coupling member are screwed 70 together.

75

together, said ring defining at its upper inner edge a pump engaging seat and having formed integrally therewith downwardly and inwardly extending hold-down fingers for engaging the annular shoulder on the pump below the seating shoulder thereon.

5. An anchoring structure for insertion in well tubing to support a pump provided with a seating shoulder and an annular shoulder therebelow for receiving resilient hold-down fingers, said anchor structure comprising a pair of coupling members adapted to be joined together and at-

tached to a well tubing string, a ring having a pump-supporting seating surface at its upper end and having formed integrally therewith downwardly and inwardly extending hold-down fingers for engaging the annular shoulder on the pump below the seating shoulder thereon, said coupling members being adapted to clamp and support said ring between them when said coupling members are joined together.
